United States Patent Office

Des. 211,286
Patented June 4, 1968

211,286

WIRE BENDER OR SIMILAR ARTICLE

Peter P. Del Monica, 10 Landon Drive,
Bordentown, N.J. 08505

Filed Aug. 17, 1967, Ser. No. 8,300

Term of patent 14 years

(Cl. D54—13)

The figure is a perspective view from the top and one side of the wire bender or similar article showing my new design.

The sides not shown are substantially plane and unornamented, and follow the specific contours as indicated.

I claim:

The ornamental design for a wire bender or similar article, substantially as shown and described.
